TRAY

David Douglas, 1119 Lincoln Blvd.,
Manitowoc, Wis. 54220

Filed Sept. 8, 1967, Ser. No. 8,528

Term of patent 14 years

(Cl. D44—10)

FIG. 1 is a top plan view of a tray or similar article embodying my design;

FIG. 2 is a bottom plan view of said tray;

FIG. 3 is a side view of said tray; and

FIG. 4 is a sectional view taken along line 4—4 of FIG. 1.

I claim:

The ornamental design for a tray, substantially as shown.
